UNITED STATES PATENT OFFICE.

WILLIAM H. TOBUREN, OF FAIRMONT, NEBRASKA.

BAND-HOLDER.

1,372,109.

Specification of Letters Patent. Patented Mar. 22, 1921.

Application filed March 2, 1918. Serial No. 220,008.

To all whom it may concern:

Be it known that I, WILLIAM H. TOBUREN, a citizen of the United States, residing at Fairmont, in the county of Fillmore and State of Nebraska, have invented certain new and useful Improvements in Band-Holders, of which the following is a specification, reference being had to the accompanying drawings.

This invention relates to an improved band holder and has for its primary object to provide a very simple device for holding the low speed, reverse and brake bands on the respective drums of the transmission mechanism of a motor vehicle while the transmission cover is being removed or replaced.

It is a more particular object of my invention to provide a device for the above purpose consisting of a single U-shaped metal rod which is adapted to straddle the spaced ends of the several bands whereby the latter are held against turning movement on the respective drums, and means attached to said rod to prevent the same from dropping to the bottom of the transmission case and to facilitate its removal after the cover has been replaced.

It is also a further general object of my invention to provide a device of the above purpose which is exceedingly simple and can be manufactured at relatively small cost and is highly serviceable for the purpose in view.

With the above and other objects in view, the invention consists in the improved form and construction of the several parts of the device as will be hereinafter more fully described, subsequently claimed and illustrated in the accompanying drawings in which similar reference characters designate corresponding parts throughout the several views and wherein;

Figure 1 is a perspective view illustrating the manner of application and use of my invention; and

Fig. 2 is an enlarged detail elevation of the band holder.

Referring in detail to the drawing, 5 designates a rod or bar of requisite diameter which is bent into substantially U-shaped form to provide the parallel arms 6 connected by the intermediate portion 7.

The low speed, reverse and brake bands of the power transmission mechanism of a motor vehicle as indicated at B are pro-

vided in the Ford type of motor vehicle at their upper sides with the angularly upwardly projecting lugs b in which the several pedal shafts are operatively engaged. 60 In assembling these bands upon the respective drums and replacing the transmission cover prior to the mounting of the pedal shafts in operative positions, considerable difficulty has heretofore been experienced 65 in retaining the bands in their proper relative positions. This difficulty I have obviated by means of the present invention.

In using the device, after assembling the several bands upon the drums, the arms 6 70 are disposed horizontally against the outer sides of the terminal lugs 6, thereby preventing sliding or separation of the ends of the bands and holding them in frictional contact upon the ends of the 75 drum. The transmission cover may now be arranged upon the lower section of the case and securely bolted in place. A chain or other flexible element indicated at 8 is attached at one of its ends to the intermediate 80 portion 7 of the rod 5 and by means of this chain, the rod 5 may be pulled longitudinally and the arms 6 thereof disengaged from the terminal lugs b of the bands and withdrawn through the opening in the top 85 of the transmission cover. Also the liability of the rod 5 dropping into the bottom of the transmission cover is largely obviated. The device is of course applied and used in a similar manner in removing the 90 transmission cover.

From the foregoing description taken in connection with the accompanying drawing, the construction, manner of use and several advantages of my invention will be clearly 95 understood. The improved band holder is of very simple form and can be manufactured at relatively small cost. I have also found the device to be highly serviceable in practical use. The holder can of 100 course be made in various sizes and can also be produced in other forms than that illustrated in the accompanying drawings.

While I have herein shown and described the preferred form and construction of the 105 several parts, it is to be understood that the same are susceptible of considerable modification and I therefore reserve the privilege of adopting all such legitimate changes as may be fairly embodied within 110 the spirit and scope of the invention as claimed.

Having thus fully described my invention, what I claim is:

1. As an improved article of manufacture, a band holder of the character described consisting of a single U-shaped member having parallel arms adapted for frictional engagement with the terminal lugs of the bands, and means connected to the medial portion of the member for with-
10 drawing the member from its applied position.
2. A band holder of the character de-

scribed consisting of a substantially U-shaped member having side arms adapted for frictional engagement with the terminal 15 ears of the bands and provided in its medial portion with an opening.

In testimony whereof I hereunto affix my signature in the presence of two wit-
nesses.

WILLIAM H. TOBUREN.
